Primary Examiner — Marianne Pandozzi*Assistant Examiner* — Jae Liang(74) *Attorney, Agent, or Firm* — Grossman Tucker Perreault & Pfleger, PLLC(57) **CLAIM**

The ornamental design for a mug with integrated bottle opener, as shown and described.

DESCRIPTION

FIG. 1 is a bottom perspective view of a mug with integrated bottle opener in accordance with the present invention; FIG. 2 is another bottom perspective view;

FIG. 3 is a left side view thereof;

FIG. 4 is a right side view thereof;

FIG. 5 is a rear view thereof;

FIG. 6 is a front view thereof;

FIG. 7 is a top view thereof; and,

FIG. 8 is a bottom view thereof.

The broken lines are included for the purpose of illustrating the unclaimed portions of the article and form no part of the claim.
